[57] CLAIM

The ornamental design for a shoe midsole, as shown and described.

DESCRIPTION

FIG. 1 is a side elevational view of one side of a shoe midsole showing our new design;

FIG. 2 is a side elevational view of the other side of the midsole shown in FIG. 1;

FIG. 3 is a front elevational view of the midsole shown in FIG. 1;

FIG. 4 is a rear elevational view of the midsole shown in FIG. 1;

FIG. 5 is a cross sectional view taken along line 5—5 of FIG. 1;

FIG. 6 is a cross section taken along line 6—6 of FIG. 1; and,

FIG. 7 is a cross section taken along line 7—7 of FIG. 1.

The broken lines showing a shoe upper and the remaining portions of a sole are for illustrative purposes only and form no part of the claimed design.

FIG. 1

FIG. 2

FIG. 4

FIG. 3

FIG. 6

FIG. 7

FIG. 5
